(57) **CLAIM**

The ornamental design for a dog harness clasp/buckle, as shown and described.

DESCRIPTION

FIG. 1 is a perspective view of a clasp/buckle according to the present invention;

FIG. 2 is a front view of the clasp/buckle illustrated in FIG. 1;

FIG. 3 is a rear view of the clasp/buckle illustrated in FIG. 1;

FIG. 4 is a right side view of the clasp/buckle illustrated in FIG. 1;

FIG. 5 is a left side view of the clasp/buckle illustrated in FIG. 1;

FIG. 6 is a top view of the clasp/buckle illustrated in FIG. 1; and,

FIG. 7 is a bottom view of the clasp/buckle illustrated in FIG. 1.

The broken line showing is included for the purpose of illustrating environment and forms no part of the claimed design.

1 Claim, 7 Drawing Sheets
